WELL PUMPING AND FLOWING MECHANISM

Roy C. Williamson, Fort Worth, Tex.

Application June 24, 1935, Serial No. 28,077

6 Claims. (Cl. 103—233)

My invention relates to pumping and flowing mechanism for wells and the like, and more particularly to a plurality of combination valves disposed at various elevations in the delivery pipe of a well and adapted to utilize the pressure of the well for raising the fluid therefrom.

The object of this invention is to provide a simple inexpensive form of valves or units which are so constructed as to fit between the sections 10 of a delivery pipe of a well and be adjusted so as to actuate at a predetermined time for intermittently retaining a column of liquid in the pipe and to admit a charge of pressure from the well to lift the column of liquid.

Another object is to provide a simple valve structure for pumping or flowing wells which will operate more efficiently in creating a low gas-oil ratio.

An advantage of this invention is that the 20 structure permits the use of the pressure of the well to lift the fluid therefrom with the minimum amount of friction of the pressure with the fluid.

Another advantage of this structure is that the 25 pressure of the well may be utilized to actuate the cores of the valves so that they will rotate in their seats, thus eliminating a considerable amount of erosion of the same and insure a more perfect seating of the valves.

Still another advantage of this invention is that each unit is so constructed as to actuate in a delivery pipe independent of the other units and in a manner so that if one should fail to function in the normal manner it will not hinder 30 the normal action of the others.

Other objects and advantages will be fully explained in the following description and the invention will be more particularly pointed out in the description.

Reference is had to the accompanying drawing which forms a part of this application.

Fig. 1 is a vertical section of a well, showing the delivery pipe thereof provided with a plurality of these pumping or flowing units disposed 45 therein and arrows indicating the pressure and fluid flow.

Fig. 2 is a vertical section of one of the valves.

Fig. 3 is a side elevation of the cage of the fluid valve unit of the device.

Fig. 4 is a similar view of the base member thereof.

Fig. 5 is a vertical section of the housing for one of the units showing the valve moved to a position to admit pressure into the pipe for elevating the fluid.

Fig. 6 is a plan view of the device, showing the openings for admitting the well pressure into the housing at an angle to utilize the pressure for rotating the valve cage.

Fig. 7 is a plan view of the fluid valve and 5 seat.

Fig. 8 is a vertical section of the same, showing a portion of the cage.

Fig. 9 is a side elevation of the upper portion 10 of the cage of the pumping and flowing unit, showing the provision of fluid seal therefor in connection with a sectional portion of the valve housing.

Similar characters of reference are used to indicate the same or similar parts throughout 15 the several views.

The device consists of a combination valve adapted to control the fluid of a well and the pressure so that the pressure of the well will elevate the fluid in stage lifts. The well may 20 be conditioned so as to retain its natural pressure or artificial pressure may be inserted for lifting the fluid therefrom. In this instance the casing 1 of the well is provided with a cap 2 having facilities for forcing pressure into the 25 casing and around the delivery pipe 3.

The combination valve, which is placed at various elevations in the delivery pipe 3 of the well, consists of a cylindrical housing 4, preferably of a diameter similar to the diameter of the pipe 30 3. These housings may be carried in the pipe by means of the conventional joints 5 used in connection of the sections of the pipe 3. Each housing is constructed in a like manner so that the parts thereof may be interchangeable. A 35 fluid valve is slidably positioned in the housing 4 so that it may reciprocate longitudinally therein and serve to open and close the pressure ports admitting pressure from the well casing 1 into the pipe 3 and lift the fluid therein.

The fluid valve of the device consists of a cage having an upper member 6 and a lower member 7 which are held rigid with each other by means of a collar 8. The collar 8 is provided with both interior and exterior annular threads 45 and is adapted to hold a valve seat 9 in the cage member 6 of the device.

The valve seat 9 is held in the upper valve cage member 6 by means of the collar 8 being screwed into the base of the member 6 and against the 50 seat 9 so that the seat will be forced against an interior annular shoulder 10 of the cage member 6. A gate valve 11 is pivotally supported in the seat 9 by means of pins 12 which are made integral with the valve 11 and adapted to project 55

into slots 13 of the valve seat 9, as shown in Fig. 7. A pin or projection 14 is made integral with the top of the valve 11 so that when the valve is opened the pin 14 will rest upon the upper surface of the seat 9 and hold the valve 11 from opening to a position where the weight of the fluid in the pipe 3 would not cause the valve to be closed.

The upper member of the valve cage is constructed with three different diameters, the larger diameter being on the base thereof and formed so as to form a shoulder with the center of the same which will act to engage an interior annular shoulder 15 of the housing 4, when the valve cage is in normal position. The body of the member 6 is constructed to have a close fit with the interior of the housing 4 and serve as a valve for closing the ports admitting well pressure into the pipe 3. The upper portion 20 of the member 6 is of the smallest diameter and serves to distort the charge of well pressure admitted to the pipe 3 so that there will be less tendency of the pressure to have a cutting action on the oil when pumping or flowing oil wells.

The lower cage member 7 is provided with an integral base formed into a bell shaped spreader 16 for permitting fluid to pass therethrough with the least amount of friction. The top of the member 7 is provided with exterior annular threads adapted to thread into the collar 8 for making the same integral with the upper cage member 6. This arrangement of the cage with the valve 11 permits the fluid of the pipe 3 to pass through the center of each unit, and the position of the valve and its structure permits the movement of the fluid to cause a reciprocating movement of the valve 11 and its cage within the housing 4 of the device.

The valve 11 and its cage, consisting of the members 6 and 7, are resiliently mounted in the housing 4 of the device so that when the fluid of a well is raised in the pipe 3, the weight of the column of fluid above the valve 11 will cause its cage to gravitate against the tension of the resiliency of the same and this action serves to admit pressure from the well casing 1 into the delivery pipe 3 of the well.

The housing 4 is provided with a plurality of lateral side openings or ports 17 which permit the pressure to pass through the housing 4 and into the pipe 3. These ports 17 are positioned so as to register with the body of the member 6 of the valve 11, when the valve is in its normal position or when the valve 11 is open for admitting fluid to pass through the pipe 3. When the weight of the fluid column above the valve 11 is of sufficient extent to move the valve cage, the cage will be forced against its resilient support and bring the upper smaller diameter 18 in alignment with the ports 17 and permit the well pressure to be directed into the housing 4 and against the outer periphery of the portion 18 of the member 6. This direction of the force or charge of pressure from the well into the pipe 3 utilizes the same for turning the valve cage so that it will have a more perfect seat against the shoulder 15 of the housing and will minimize the erosive effect on its seat. When the ports 17 are drilled anagularly to the center of the housing, as shown in Fig. 6, the force of the pressure will attack the surface of the member 6 at an angle and will tend to rotate the same so that the larger diameter of the member 6 will not seat against the shoulder 15

of the housing 4 in a constant or uniform manner, thus insuring a more perfect seating of the same.

The resiliency of the valve cage consists of supporting the cage in the housing 4 by means of a coil spring 19. The spring 19 is carried around the upper end of the member 7 and adapted to rest upon an interior shoulder 20 of a collar 21. The collar 21 is provided with exterior threads which are adapted to screw into the base of the housing 4. The upper end of the spring 19 bears against the connecting collar 8 of the two members 6 and 7, and its tension between the members 8 and 21 determine the amount of weight required to actuate the cage to open the ports 17 and admit pressure from the well into the pipe 3 for raising the liquid in the pipe 3.

An interior annular shoulder 22 is provided in the housing 4 of the device for permitting the member 21 to be held in a rigid state in the housing and insure perfect adjustment of the tension on the valve cage. The member 21 may be screwed into the housing 4 until it bears against the shoulder 22 or a washer member 23 may be interposed between the top of the member 21 and the shoulder 22 for varying the position of the member 21 in the housing 4. This collar 23 may be formed as a lock washer for more securely holding the member 21 at a pre-determined position within the housing 4, as shown in Fig. 5.

When a plurality of these valves are positioned at various elevations in the delivery pipe of the well, the pressure in the casing 1 will bear against the fluid in the well and cause the same to rise up the pipe 3 and pass through the lower one of the units. When the fluid has passed through the pipe 3 and one or more of the units, its weight will cause the valves 11 of those units that it has passed through to force the cages against their springs 19 until the ports 17 are opened. When the pressure from the well passes through these ports 17 it will further raise the liquid, and this action will be continued intermittently throughout the plurality of combination valves in the pipe 3, thus causing a stage lift of the fluid in the well. This arrangement uses the movement of the fluid to actuate the valve to open the ports 17 and permit the pressure of the well to be utilized for flowing or pumping the well.

In Fig. 9, the upper member 6 of the valve cage is provided with a plurality of annular exterior grooves 25 positioned therein to serve as a fluid seal above and below the ports 17, when the valve is in normal position. This structure facilitates fluid packing or fluid sealing structure in wells of such condition that will not permit of the conventional pumping structure.

When the pressure of the fluid above one of these combination valves or units actuate the parts thereof to admit the pressure medium to the fluid, the pressure charge first strikes the metallic member 18 that directs the same to travel, in what might be termed a spiral direction and in close proximity up the inner walls of the pipe 3 and around the column of fluid during the lift thereof. This means of directing the pressure medium in this manner eliminates an abrupt entry of the same into the column but permits the same to eventually enter the column during the lift of the liquid, thus minimizing the cutting effect of the pressure medium on the fluid lifted.

What I claim is:

1. A well pumping and flowing mechanism comprising a delivery pipe, a plurality of valves disposed at various elevations in said pipe and adapted to intermittently retain a column of fluid in said pipe and to admit pressure from said well into said column of fluid for lifting the same, and means for directing said pressure against the inner sides of said delivery pipe so that same will be uniformly distributed in said fluid as it lifts the same. 5
2. A well pumping and flowing mechanism comprising a delivery pipe having a plurality of valves disposed at various elevations therein, said valves being adapted to intermittently retain a column of fluid in said pipe and to admit a charge of pressure from said well into said column of fluid for lifting the same, and means for utilizing said charge of pressure for turning the cores of said valves. 10
3. A well pumping and flowing mechanism consisting of a plurality of valves disposed at various elevations in a delivery pipe, said valves being adapted to intermittently retain a column of fluid in said pipe and to admit a charge of pressure from said well into said fluid for lifting the same, and means for utilizing said charge of pressure for turning the cores of said valves for minimizing the erosion thereof and insure 15 a more perfect seat thereof. 20
4. A well pumping and flowing mechanism for wells consisting of a delivery pipe having a plurality of valves disposed at various elevations 25
5. A well pumping and flowing mechanism for wells and the like consisting of a delivery pipe, a plurality of control units disposed at various elevations in said pipe and adapted to intermittently retain a column of fluid in said pipe and to admit pressure from said well for lifting said fluid, and said units being formed to direct said pressure against the inner periphery of said delivery pipe and relative to said fluid so that the same will gradually impregnate the fluid during 30 the lift thereof. 20
6. A well pumping and flowing mechanism for wells and the like consisting of a delivery pipe, a plurality of control units disposed at various elevations in said pipe and adapted to intermittently retain a column of fluid in said pipe and to admit pressure from said well for lifting said column of fluid, and said units being arranged to control the said pressure so that it will tend to travel around said column of fluid until it gradually impregnates the same during 30 the lift thereof. 25
